his Attorney.

UNITED STATES PATENT OFFICE.

LOUIS O. LIEBER, OF LOS ANGELES, CALIFORNIA.

UNIVERSAL LAMP-BASE.

1,231,758.

Specification of Letters Patent.

Patented July 3, 1917.

Application filed December 27, 1915. Serial No. 68,796.

To all whom it may concern:

Be it known that I, LOUIS O. LIEBER, a citizen of the United States, residing at Los Angeles, in the county of Los Angeles, State of California, have invented new and useful Improvements in Universal Lamp-Bases, of which the following is a specification.

This invention relates generally to a connecting or joint forming device which is particularly useful as a universal lamp base adapted to be inserted in any kind of a lamp socket; or it is particularly useful for any similar kind of electrical connection.

It is an object of this invention to provide a simple joint forming, electrical contact device which may be put together or released by a comparatively small movement; which may be manipulated quickly and without the necessity of rotation through more than a small part of a complete revolution. As applied to lamp bases and similar electrical connections my device has several distinctive utilities; and among these I may particularly mention the fact that an electrical connection may be made or broken very quickly with my device and also that the connections may be made or broken without the necessity of much relative turning of one part in the other. This last mentioned feature does away with the twisting of a cord which may be attached to the joint forming member; and does away with the necessity of swivel joints in electrical plugs and the like.

The nature of my invention, and the specific details of preferred forms thereof, are explained in the following specification, reference being had to the accompanying drawings, in which, for the purpose of this specification, I have illustrated preferred forms of my invention. In these drawings Figure 1 is a view, partially in section, showing my invention applied to an electric lamp, Fig. 2 is a section of the lamp base taken as indicated by line 2—2 on Fig. 1, Fig. 3 is a section similar to that of Fig. 2 showing a modified form of device, and Fig. 4 is a view similar to Fig. 1 showing my invention applied to an electric plug.

In the drawings I have illustrated a typical form of socket 10, which forms the exterior member of my connection device in the form of that device shown in Fig. 1. This socket has the usual interiorly threaded socket member 11 into which the usually screw threaded base of lamp 12 is adapted to be rotated. The lamp 12 in this instance

is provided with a plain cylindrical base 13, which is the interior member of my joint forming or connection device in the form shown in Fig. 1.

In the form shown in Figs. 1 and 2 this interior member 13 is composed of an outer cylindrical part 15 having a circumferential slot 16 extending a short distance around the member 15. Within the member 15 there is an inner part or member 14, also preferably cylindrical, and arranged eccentrically of the member 15, so that its surface forms an eccentric surface upon which the ball 17 may roll. The ball 17 rolls in the slot 16 on the eccentric surface of member 14, between the positions shown in full and dotted lines in Fig. 2. When the ball is in the position shown in dotted lines in Fig. 2, it does not project, or projects very little beyond the outer surface of member 15; while when it is in the position shown in full lines, it projects substantially beyond the outer surface of member 15, as is shown in Fig. 1. When in the position shown in dotted lines the ball should preferably project a small amount so that when the inner member 13 is turned the outer part of the ball may engage with the inner surface of the member 11 to cause the ball to roll toward its other position. The ball is of slightly greater diameter than the width of slot 16 so that the ball cannot pass wholly outwardly through the slot and drop out, the ball being retainingly carried by the interior member 13 as herein set forth. In the form shown in Figs. 1 and 2, the lamp base may be provided with the usual contact head 20; and the connection from this head 20 may pass down inside the inner cylindrical member 14, as shown at 21. The interiors of members 14 and 15 may be filled with the usual insulating substance as indicated at 22.

In using my improved lamp base, the base is inserted in any socket by a longitudinal movement and is then given a small turn. The ball 17 rolls from the position shown in dotted lines in Fig. 2 to the position shown in full lines in that figure; and in this position the ball will engage in the screw threads of the socket member 11. The power with which the ball is forced outwardly against the outer member will depend upon the extent of circumferential movement of the ball and the steepness of the incline (or eccentricity of member 14)

over which the ball rolls. The ball is forced outwardly, and the effective diametral dimension of the inner member is thus increased, the side of the inner member 13 opposite the ball being thus forced against the opposite side of the outer member to make good contact therewith. The ball rolls easily on the eccentric surface and on the outer member; but when the ball is tightly held between the two members then it becomes a kind of lock preventing the backward motion of the inner member. The rolling ball is preferred to a sliding button or block or the like for the further reason that the ball does not mar or deform the outer member by its action. In fact, it will be seen that the ball, or any equivalent member will engage in any depression or opening which may be provided in the interior surface of member 11, whether that depression or opening be helical or screw threaded or of any other form. Thus my device provides a universal lamp base which will engage in any of the usual and ordinary forms of lamp sockets; and which may be engaged by a very small turn, in fact a small fraction of a revolution. When the part 13 is used, a plug with a cord attached, it will be seen that the cord will not be twisted to any great extent when the plug is inserted in a socket. (See Fig. 4, where the plug is indicated by the numeral 13^a and the cord by numeral 12^a.) And this feature of my device eliminates entirely the necessity for any swivel connection in the plug. Moreover, in making any kind of an electrical connection with my device, it is seen that the connection is easily and quickly made, and as easily and quickly broken; and this is an important feature in enabling the quick breaking of the arc between electrical contacts. In an ordinary screw threaded socket and plug, the electrical connection is slowly broken and the contact pieces move away from each other very slowly, allowing a prolonged arc to take place between the contact pieces. In my device the contact is quickly broken and the parts may then be moved quickly away from each other.

In Fig. 3 I have shown a modified form of the inner member 10^c. Here the ball 17^c rolls in a circumferential slot 16^c and rolls on the eccentric surface of a member 14^c which need not be a complete cylinder but may extend only through a portion of the circumference of member 10^c, or may extend only behind the slot 16^c. Such variations as herein explained, and others, will occur to those skilled in the art; and I accordingly do not limit myself to the particular modifications herein explained.

It will be noted that the essential charac-

teristic of my device is the provision for operation in the manner explained; viz., insertion by longitudinal movement and locking by rotary movement, the two movements being independent of each other. In other words, the plug is longitudinally movable in the socket and rotatable therein without these two movements being interdependent as in the ordinary screw-threaded form of plug and socket.

Having described preferred forms of my invention, I claim:

1. An electrical joint forming device, embodying a hollow cylindrical outer member and a cylindrical inner member adapted for movement independently longitudinally and rotatively in said outer member, said outer member having a circumferentially elongated depression in its inner surface, a surface carried by the inner cylindrical member eccentric thereto, and a ball carried by said inner member and adapted to roll on said eccentric surface and to engage in said depression.

2. An electrical joint forming device, embodying a hollow cylindrical outer member internally screw threaded, an inner cylindrical member adapted for movement independently longitudinally and rotatively in said outer member and having a circumferential slot, and an interior surface behind said slot eccentric to the member itself, and a ball in said slot running on said eccentric surface and adapted to engage in the screw threads of the outer member.

3. An electrical joint forming device, embodying a pair of substantially cylindrical members, one freely movable independently longitudinally and rotatively within the other, a rolling locking member retainingly carried by one of the cylindrical members projecting therefrom to engage the other member, and means to cause movement of the locking member toward the other cylindrical member by virtue of relative rotation of the two cylindrical members one within the other.

4. An electrical joint forming device, embodying a pair of substantially cylindrical members, one freely movable independently longitudinally and rotatively within the other, an eccentric surface carried by one of said members, and a ball carried by said member and adapted to roll on said eccentric surface and project from the said member to engage the other member.

In witness that I claim the foregoing I have hereunto subscribed my name this 18th day of December, 1915.

L. O. LIEBER.
